(57) **CLAIM**

The ornamental design for an upper body elevator, as shown and described.

DESCRIPTION

FIG. 1 is a front perspective view of the upper body elevator; FIG. 2 is a right side view of the upper body elevator; FIG. 3 is a left side view of the upper body elevator; FIG. 4 is a top view of the upper body elevator; FIG. 5 is a bottom view of the upper body elevator; FIG. 6 is a rear view of the upper body elevator; and, FIG. 7 is a front view of the upper body elevator. The drawing disclosure of this application includes broken line depictions of a portion of the upper body elevator, which portion does not form a part of the claimed design.
